Primary Examiner — Deanna L Pratt(74) *Attorney, Agent, or Firm* — Studebaker & Brackett
PC(57) **CLAIM**

The ornamental design for a baby bouncer, as shown and described.

DESCRIPTION

FIG. 1 is a front perspective view showing our new design for a baby bouncer,

FIG. 2 is a front view thereof;

FIG. 3 is a rear view thereof;

FIG. 4 is a left side view thereof, with the opposite side being a mirror image;

FIG. 5 is a bottom view thereof;

FIG. 6 is a top view thereof; and,

FIG. 7 is a rear perspective view thereof.

The broken lines illustrate portions of the baby bouncer that form no part of the claimed design.
